(57) **CLAIM**

I claim the ornamental design for a portable mouse, as shown and described.

DESCRIPTION

FIG. 1 is a front perspective view of the portable mouse comprising the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof rotating from a first configuration depicted in FIGS. 1-7 above to a second configuration;

FIG. 9 is a front perspective view thereof in the second configuration;

FIG. 10 is a front view in the second configuration thereof;

FIG. 11 is a back view in the second configuration thereof;

FIG. 12 is a left view in the second configuration thereof;

FIG. 13 is a right view in the second configuration thereof;

FIG. 14 is a top view in the second configuration thereof; and,

FIG. 15 is a bottom view in the second configuration thereof. Broken lines shown in the drawings illustrate portions of the portable mouse, and form no part of the claimed design.
